Primary Examiner — Keli L Hill*Assistant Examiner* — Harold E Blackwell, II(74) *Attorney, Agent, or Firm* — Andrew C. Cheng(57) **CLAIM**

I claim the ornamental design for a mobile phone film applicator, as shown and described.

DESCRIPTION

FIG. 1 is a perspective view of a mobile phone film applicator showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, showing the mobile phone film applicator in a state of use.

The broken line showing of the mobile phone film applicator illustrates portions which forms no part of the claimed design.
